UNITED STATES PATENT OFFICE.

GEORGE A. TAYLOR, OF WEEHAWKEN, NEW JERSEY, ASSIGNOR TO NATIONAL BISCUIT COMPANY, OF NEW YORK, N. Y., A CORPORATION OF NEW JERSEY.

DISPLAY RACK.

1,423,585.

Specification of Letters Patent. Patented July 25, 1922.

Application filed April 27, 1921. Serial No. 464,894.

To all whom it may concern:

Be it known that I, GEORGE A. TAYLOR, a citizen of the United States, and resident of Weehawken, in the county of Hudson and State of New Jersey, have invented certain new and useful Improvements in Display Racks, of which the following is a specification:

The invention relates to display racks and particularly to racks adapted for the display of cartons or cans containing crackers, or the like, in grocery stores and similar establishments. The invention aims to provide a rack of simple and comparatively inexpensive construction which may be assembled and taken apart very easily and simply and which is adapted to be shipped in knocked-down condition. The invention also aims to provide a rack which will be pleasing in appearance, which may be readily extended by the addition of upright members and shelves, and which will be well braced and stiffened by the means of the shelves themselves, together with brackets secured to the shelves, by which brackets the shelves are secured in position between the uprights.

In the preferred form of the invention the uprights are provided with securing devices, such as bolts, at spaced intervals and the shelves are provided with brackets having openings therein, preferably slots extending from edges of the brackets, which are adapted to be positioned on the bolts to secure the shelves in position. For the display of cracker containers, or the like, it is sometimes desirable to position the shelves horizontally, and sometimes at an angle which extends downwardly from front to back. In the preferred form of the device the shelves are provided with upwardly extending back portions and the brackets referred to are mounted both on the bottom portions and the back portions of the shelves. When a shelf is to be positioned horizontally, slots on the brackets adjacent the bottom portion of the shelf are slipped over the proper aligned bolts, and when it is desired to position the shelf at an angle slots adjacent the front edge of the bottom portion of the shelf and adjacent the upper end of the back portion of the shelf are slipped over the proper bolts. The bolts are provided with nuts which are screwed up against the brackets so as to se-

cure the shelves rigidly in position and to cause the shelves themselves to form braces, or struts, by which the uprights are firmly held in position to make the entire construction rigid. In the preferred construction the bolts extend from both sides of the uprights so that the rack may be extended by securing shelves to the outer sides of the end uprights, such additional shelves having, of course, uprights at their outer ends.

The objects of the invention are to provide an improved and efficient construction of the character indicated, and also to provide improved forms of construction and combinations of parts, all as will be more fully set forth in the following specification, and particularly pointed out in the appended claims.

In order that the invention may be more clearly understood, attention is hereby directed to the accompanying drawings forming part of this application, and illustrating certain embodiments of the invention. In the drawings,

Fig. 1 represents a front elevation of a rack embodying the invention;

Fig. 2 is a vertical section taken on line 2—2 in Fig. 1;

Fig. 3 is a vertical section taken on line 3—3 in Fig. 1;

Fig. 4 is a partial enlarged section through a pair of shelves mounted in position;

Fig. 5 is a similar view showing a back extension piece used as a division strip mounted in position on an inclined shelf;

Fig. 6 is a partial perspective view showing a shelf mounted in position with a back extension about to be mounted on the back portion of the shelf;

Fig. 7 is a view similar to that shown in Fig. 4, illustrating a modified form of the invention, this view being taken on line 7—7 of Fig. 8;

Fig. 8 is a front elevation of the construction shown in Fig. 7;

Fig. 9 is a view similar to that shown in Fig. 7, showing a further modification of the invention, this view being taken on line 9—9 of Fig. 10; and

Fig. 10 is a front elevation of the construction shown in Fig. 9.

Referring to the drawings, the rack may employ a plurality of upright members 1, 1, each of which preferably comprises a front post or member 1^a and a back post or mem-

ber 1^b, these posts being secured together by horizontal members 2 and a base portion 3.

The shelves 4 are preferably provided with back portions 5 which extend upwardly from the rear edges of the bottom or supporting portions of the shelves, the back portions 5 preferably being of a height which is less than the distance from front to back of the bottom portion of each shelf. 10 The shelves, as well as the upright members, may be formed of any suitable material, preferably of wood.

The shelves may be positioned horizontally, as is indicated for example in Fig. 3, 15 with the containers 6 resting thereon and bearing against the back portions 5 of the shelves, or these shelves may be mounted at an inclination which extends downwardly from the front to rear, as is indicated for 20 example in the lower portion of Fig. 2, so that the containers will rest partly on the portion 4 and partly on the portion 5 of the shelf, with the fronts of the cartons inclined upwardly and rearwardly, for the better 25 display of the goods therein.

The upright members are provided with securing devices such as the bolts 7 which extend laterally from the posts comprising the upright members. Preferably the bolts 30 either extend all the way through the uprights, with threaded portions on both ends, or else separate bolts may be positioned in the uprights to extend from the opposite sides thereof in alignment with each other. 35 The bolts 7 are positioned at properly spaced intervals so that shelves may be mounted in position above the same with a proper vertical distance between shelves.

In the form of the invention illustrated in 40 Figs. 1 to 5 inclusive each bottom portion 4 of a shelf is provided with a pair of brackets adjacent the front edge thereof. One of these brackets is mounted adjacent to one side edge of the shelf and the other adjacent to the opposite side edge of the shelf, each bracket being of angular construction with a flange 8 secured to the underside of the shelf and a downwardly extending flange 9, at the outer edge of the shelf. At the rear 45 of the shelf a pair of similar brackets are provided having flanges 8¹ which are secured to the underside of the shelf and downwardly extending flanges 9¹, these brackets, as well as the front brackets, being made 50 righthand and lefthand.

In the form of construction being described, each back portion 5 of the shelf is provided with a pair of brackets, one for each side of the same, these brackets each 60 comprising a flange 10 which is secured to the back of the back portion 5 of the shelf, and a forwardly extending flange 11, which extends forwardly past the side edge of back portion 5. The flanges 9 and 9¹ of the 65 brackets underneath the shelf are provided

with slots 12 which extend upwardly from the lower edges of the flanges, and the flange 11 of each bracket secured to a back portion 5 is provided with a slot 13 which extends upwardly from the lower edge of the flange. 70 Preferably the slots 12 extend in a direction at right angles to the surfaces of the bottom portions 4 of the shelves, while the slots 13 preferably extend at an upward and forwardly directed angle to the surfaces of the 75 back portions 5 of the shelves.

With this construction shelves may be mounted horizontally between adjacent uprights by simply slipping the slots 12 beneath the shelf over the horizontally aligned 80 bolts 7, as is indicated for example in Fig. 3, and then tightening the nuts on bolts 7. Or, if certain shelves are to be mounted in an inclined position, the slots 12 of the brackets at the front of the shelf are slipped 85 over the aligned front bolts 7 and slots 13 of the back flanges 11 are slipped over the corresponding bolts 7 at the rear, and the nuts tightened on the bolts. In either case the uprights will be held together and braced 90 in position by the shelves.

It is sometimes desired to provide a higher back for a shelf and this may readily be accomplished by the provision of a back extension member 14 which may be removably secured in position upon the upper edge of a back portion 5 of a shelf. Preferably all of the back extension members 14 are provided with downwardly extending dowel pins 15 which are adapted to fit into corresponding openings 16 which are formed in the upper surfaces of all of the shelf back 100 portions 5.

It is also sometimes desired to divide the shelves into compartments or to provide a 105 shelf space of only half the usual depth, for example to hold containers of less than the usual width from front to back. This can readily be accomplished by the provision of members 17, which I may term division 110 strips. These members may be, and preferably are, the same as the back extension members 14, which may be used interchangeably. Each of the bottom portions 4 of the shelves is preferably provided with openings 115 18 which may extend in a line parallel with the front and back edges of the shelf. Each division strip 17 is provided with downwardly extending dowel pins 19, as indicated in Fig. 5, which are adapted to fit into 120 openings 18 to removably secure the division strip in position.

Another form of construction which is in certain ways superior to the construction previously described, is illustrated in Figs. 125 7 and 8. In this construction the separate brackets previously described as secured to the bottom and back of each shelf are replaced by a single angular bracket mounted at each end of the shelf. This may take 130

the form of a metallic member having a bottom flange 20 secured to the underside of the bottom portion 4 of the shelf, and a flange 21, which may be an extension of flange 20, bent at right angles thereto, secured to the rear surface of the back portion 5 of the shelf. A vertical flange 22 extends downwardly from the outer edge of flange 20 and a vertical flange 23 extends rearwardly from the outer edge of flange 21. Each flange 22 is provided with a slot 24 extending upwardly from its lower edge adjacent the front end of the flange, and with a similar slot 25 adjacent the rear end of 15 the flange. Flange 22 is also provided with a slot 26, somewhat to the rear of slot 24, slot 26 preferably being inclined upwardly and forwardly. Each flange 23 is provided with a slot 27 which extends forwardly from 20 the rear edge of the flange.

Each shelf is provided with a pair of the brackets described, one adjacent its right-hand edge and the other adjacent to its left-hand edge, the brackets being, of course, 25 made righthand and lefthand so that the vertical flanges 22 and 23 will be at the outer edge of the brackets in each instance. A shelf is mounted in horizontal position with horizontally disposed bolts 7 engaging with 30 in slots 24 and 25 and the shelf is mounted in inclined position by seating bolts 7 at the front in slots 26 and slipping the rear slots 27 over the corresponding rear bolts. The shelves are, of course, secured in position 35 by screwing up the nuts of bolts 7. In this form of construction the flanges 20 and 21 extend for the full width of the bottom portion and the full height of the back portion 5 respectively, so that the brackets will 40 greatly stiffen and reinforce the construction.

A very similar construction is shown in Figures 9 and 10 in which, however, the vertical flange 23¹ at the back extends forwardly from flange 21 which is secured to the rear surface of back portion 5, instead of extending rearwardly, as does the flange 23 in the construction shown in Fig. 7. The flange 22¹ extends downwardly from the 45 outer edge of flange 20 which is secured beneath bottom portion 4 of the shelf. Flange 22¹ corresponds to flange 22 described in connection with Fig. 7, except that slot 26¹ is somewhat differently spaced from the corresponding slot 26 shown in Fig. 7, because 50 of the fact that flange 23¹ extends forwardly, at one side edge of back portion 5 while flange 23, previously described, extends rearwardly. With this construction the shelf 55 is mounted horizontally with slots 24 and 25 engaging the bolts, or it is mounted in inclined position with slots 26¹ and 27¹ engaging the bolts, slot 27¹ corresponding to the slot 27 described in connection with Fig. 60 7, but preferably being inclined, as shown.

It will be noted that the various constructions described provide for the ready removal of shelves or mounting of shelves in desired positions and that the rack may be extended at either end by simply securing 70 additional shelves on the bolts 7 which extend from the outer surfaces of the end uprights of the rack, these additional shelves being, of course, provided with additional end uprights.

It should be noted that the invention is not strictly limited to the details of construction which have been particularly described, but that the same is as broad as is indicated by the accompanying claims. 75 80

What I claim is:

1. In a display rack, the combination of upright members, securing devices extending from the same at spaced intervals, and shelves adapted to extend between adjacent 85 upright members, having bottom portions and back portions extending upwardly from the rear edges thereof, said shelf back and bottom portions having securing devices thereon adapted to coact with said first 90 named securing devices, to support said shelves in horizontal position or in inclined position from back to rear, as desired.

2. In a display rack, the combination of upright members having bolts extending 95 from both sides of the same at spaced intervals, in the lengthwise direction of the rack, shelves adapted to extend between adjacent upright members, and brackets secured to said shelves having slots therein adapted to 100 fit over said bolts to support said shelves, said bolts having nuts for holding said brackets in position, said brackets being adapted to fit over the portions of said bolts extending from either side of an upright 105 member, so that the rack may be extended at will by the addition of shelves and upright members.

3. In a display rack, the combination of upright members, having front and rear 110 portions, shelves, adapted to extend between adjacent upright members, brackets secured to said shelves and securing devices extending from said upright members, said brackets having upwardly extending slots therein, 115 positioned and adapted to fit over said securing devices to support said shelves in either horizontal position or inclined from front to rear, as desired.

4. In a display rack, the combination of 120 upright members, having front and rear portions, shelves, adapted to extend between adjacent upright members, having bottom portions, and back portions extending upward from the rear edges thereof, brackets 125 secured to said bottom and back portions, and securing devices extending from said upright members, said brackets having openings therein adapted to fit over said securing devices, to support said shelves in 130

horizontal position when openings in said brackets adjacent to said bottom portions engage said securing devices, and to support said shelves in position inclined from front to rear when openings in said brackets adjacent to said bottom and back portions engage said securing devices.

5. In a display rack, the combination of upright members, having front and rear portions, shelves, adapted to extend between adjacent upright members, having bottom portions, and back portions extending upwardly from the rear edges thereof, a bracket member secured to the bottom portion of each shelf, having a downwardly extending flange with slots extending upwardly from its lower edge, adjacent the front and rear ends thereof, and a bracket member secured to the back portion of each shelf, having a slot therein, and bolts extending laterally from said upright members, so positioned that said shelves may be mounted horizontally with forward and rear slots of said first named bracket members positioned on front and rear bolts, or that said shelves may be mounted at a rearwardly extending inclination with forward slots of said first named bracket members and slots of said second named bracket members positioned on front and rear bolts, respectively.

6. In a display rack, the combination of upright members having bolts extending laterally from the same at spaced intervals, shelves adapted to extend between adjacent upright members, said shelves having bottom portions and back portions extending upwardly from the rear edges of said bottom portions, brackets secured to said shelves having openings therein adapted to

fit over said bolts to support said shelves in either horizontal position or a position inclined from front to back, and members adapted to be removably secured on the upper edges of said back portions, as back extensions, or to be removably secured on said bottom portions of the shelves, as division strips.

7. In a display rack, the combination of upright members, shelves adapted to extend between adjacent upright members, having bottom portions, and back portions extending upwardly from the rear edges thereof, brackets secured to said shelves adjacent the side edges thereof, having flanges extending from front to rear of the bottom portions and from top to bottom of the back portions, secured to the under and rear surfaces of said bottom and back portions respectively, and flanges extending from the edges of said first named flanges, in vertical planes, said lower vertical flanges having slots extending upwardly from their lower edges adjacent the front and rear ends thereof and said back vertical flanges having slots in the free edges thereof, and bolts extending laterally from said upright members, so positioned that said shelves may be mounted horizontally with forward and rear slots of said lower flanges positioned on front and rear bolts, or that said shelves may be mounted at a rearwardly extending inclination with forward slots of said lower flanges and slots of said back flanges positioned on front and rear bolts, respectively.

Signed at New York, N. Y., in the county of New York and State of New York this 25th day of April A.D. 1921.

GEORGE A. TAYLOR.
